CLAIM

The ornamental design for a saucepan, as shown and described.

DESCRIPTION

FIG. 1 is a front view of a saucepan according to my design; FIG. 2 is a right side view thereof, with the left side view being a mirror image thereof;

FIG. 3 is a bottom view thereof;

FIG. 4 is an exploded bottom perspective view thereof; shown with the pan and the lid being separated for ease of illustration; and,

FIG. 5 is an exploded top perspective view thereof, shown with the pan and the lid being separated for ease of illustration.
